The ornamental design for a medical robotic cart as shown and described.

DESCRIPTION

FIG. 1 is top front left perspective view of a medical robotic cart showing our new design;

FIG. 2 is top rear right perspective view of the design shown in FIG. 1;

FIG. 3 is a bottom view of the design shown in FIG. 1;

FIG. 4 is a top view of the design shown in FIG. 1;

FIG. 5 is a right side view of the design shown in FIG. 1;

FIG. 6 is a front view of the design shown in FIG. 1;

FIG. 7 is a left side view of the design shown in FIG. 1; and,

FIG. 8 is a rear view of the design shown in FIG. 1.

The broken lines shown in the figures are included for the purpose of illustrating portions of the medical robotic cart and form no part of the claimed design.
